UNITED STATES PATENT OFFICE.

GEORGE F. DILLIG, OF PITTSBURGH, PENNSYLVANIA.

LOADING MECHANISM.

1,281,582.

Specification of Letters Patent.

Patented Oct. 15, 1913.

Application filed July 3, 1916. Serial No. 107,348.

To all whom it may concern:

Be it known that I, GEORGE F. DILLIG, residing at Pittsburgh, in the county of Allegheny and State of Pennsylvania, a citizen of the United States, have invented or discovered certain new and useful Improvements in Loading Mechanism, of which improvement the following is a specification.

The invention described herein relates to certain improvements in loading mechanism, especially to the class or type used in confined places, as mines or tunnels, and has for its object a construction in which the scoop moves in the arc of a circle, with which the surface from which the material is to be removed, is tangential or approximately so, said arc of movement passing in such proximity to a receiving hopper that by the movement of the scoop around a second axis, the material may be discharged into the receiving hopper. The invention is herein-after more fully described and claimed.

In the accompanying drawing forming a part of this specification, Figure 1 is a side elevation of a loading mechanism embodying my improvements; Fig. 2 is a top plan view of the same, the transfer mechanism being omitted; Fig. 3 is a detail view of the reversible mechanism employed for moving the scoop; and Fig. 4 is a sectional elevation on an enlarged scale, the left half being on a plane indicated by the line $x-x$ and the right half by the line $y-y$, Fig. 1.

In the practice of the invention, a box shaped structure 1 is mounted on axles 2, having wheels 3 adapted to move along rails 4. The box has an open top and is provided with, adjacent to its front end, a circular truck 5 on which is mounted the annular base 6 of the boom or out-rigger 7. Suitable means, such as a sectional ring 8 can be employed for holding the boom or out-rigger in position on the track. Provision is made for the rotation or lateral shifting of the boom 45 by any suitable means, such, as for example, that shown, consisting of a driven pinion 9 intermeshing with teeth formed on the periphery of the sectional clamping ring 8. At a suitable distance from the outer or free 50 end of the boom, is mounted a shaft 10 on which are secured the upper ends of arms 11 and also a sprocket wheel 12 for rotating the shaft, as hereinafter described. In suitable bearings in the lower end of the arm 11

is mounted a shaft 13 on which are keyed hubs 14 provided with suitable flanges 15, adapted to be secured to the scoop 16. A sprocket wheel 17 is also connected to shaft 13 and is operatively connected by a chain 18 to the sprocket wheel 12 on shaft 10, so that by the rotation of the latter, the scoop may be rotated as hereinafter described.

The movement of the scoop around the axis of the shaft 10 is effected by means of wire ropes 19 and 20, passing in opposite directions around a drum 22. As the movement of the scoop forward to gather up the material, will meet with considerable resistance, it is preferred that the pull necessary to effect such scooping movement should be applied to both ends of the shaft 13, so that there will not be any twisting of the mechanism, when gathering material. As shown in Fig. 2, the front portion of the rope 19 is divided, said parts being connected to the shaft 13 and passing around guide pulleys 23, 24 and 25, mounted on the boom, whereby the ropes are brought into line, and united to form a single strand passing around the winding drum. As there will be little resistance to the movement of the scoop after being changed to a position to discharge into the box or body of the car, a single rope 20 will be sufficient. This rope passes from one end of the shafts over guide pulleys 26, 27, 28, 29 and 29, on to the winding drum. The ropes 19 and 20 are wound in opposite directions upon the drum so that when the drum is rotated to wind up one of the ropes, the other rope will be let off the drum at an equal rate.

On the shaft of the drum 22 is keyed a gear wheel 30 which intermeshes with a pinion 31, loosely mounted on the shaft 32, which is driven through suitable connections by the motor 33. When it is intended to operate the drum in one direction, a clutch 34, which is keyed on the shaft 32 with freedom of movement longitudinally thereof, is shifted so as to engage the pinion 31 and cause the latter to rotate and drive the gear-wheel 30 and the winding drum. For the reverse movement of the drum, the clutch 34 is shifted to engage the pinion 35 loosely mounted on the shaft 32 and intermeshing with the pinion 36 on the shaft 37. On this same shaft is keyed a pinion 38 also intermeshing with the gear-wheel 30. When driving

through the pinion 35, the gear-wheel 30 will rotate in the opposite direction from that imparted to it by the pinion 31.

- The rotation of the shaft 10 whereby, 5 through the medium of the sprocket wheels 12 and 17 and the chain 18, the shaft 13 is rotated to turn the scoop, is effected by a sprocket wheel on the shaft 39, a chain 40 passing around said sprocket-wheel and a 10 similar wheel 12^a on the shaft 10. The rotation of the shaft 39 is effected in substantially the same way as the rotation of the drum. On the shaft 32 is loosely mounted a pinion 41 adapted to intermesh 15 with a gear wheel 42 keyed to the shaft 39, said pinion being adapted to be connected to the shaft 32 by a clutch 43, keyed on the shaft, but free to move longitudinally thereof, so as to engage the pinion 41 20 or the pinion 44 loosely mounted on the shaft 32 and intermeshing with the pinion 45 on the shaft 37^a. On this same shaft 37^a, is keyed a pinion 46 adapted to intermesh with the gear-wheel 42. By shifting 25 the clutch 43, into engagement with the pinion 44, the direction of rotation of the pinion 42 is reversed and through such reversal, a reverse turning movement of the scoop is also effected.
- 30 The car and parts carried thereby, having been shifted into suitable relation to the material to be loaded, the scoop is turned to the position shown in Fig. 1. The drum 22 is then operated so as to draw in the rope 35 19, thereby causing the scoop to move forward to gather up material in the arc of the circle around the axis of the shaft 10. At the same time, or shortly after, the scoop has begun to move around the axis of the 40 shaft 10, the shaft 13 is rotated so that the scoop will turn toward an upright position, so as to retain the gathered material. These movements of the scoop around the axes of the shaft 10 and 13 may be effected simultaneously or the movement around the shaft 45 10 may be started somewhat before the movement around the shaft 13 to an upright position is begun. After the scoop has been charged in the manner above stated, the direction of rotation of the drum 22 is reversed so that the scoop will be moved toward the left in Fig. 1 and at the same time the turning of the scoop around the shaft 13 is continued, so that by the time the scoop 50 55 will be swung to the left into suitable proximity to the receiving hopper or car, it will also have been turned around the shaft 13 so as to discharge its contents into the hopper or car.
- 60 Provision is made preferably by means of a traveling belt, for the removal of the material from the receiving hopper or car, to a car whereby the material can be withdrawn from the point of loading. In 65 the construction shown, a belt 48 of any

suitable construction, is passed around wheels 49 and 50, the former being so arranged within the car that material dumped into the latter will be directed by an apron 51 on the belt. The wheel 50 is mounted in 70 suitable bearings on the upper end of an upwardly inclined arm 52, projecting such a distance in the rear of the loading truck or car as to permit the passage of the transfer car 53 into position underneath its outer 75 end. The wheel 50 is so constructed as to engage and move the carrying belt, and the shaft 54 on which such wheel is mounted, has a sprocket-wheel 55 keyed thereon, and around this wheel 55 and the driven sprocket-wheel 56 is passed a chain 57. On the shaft of the wheel 56 is keyed a worm wheel adapted to be engaged by a worm 58 on the driving shaft 39. This shaft is driven by a motor 60 through a pinion and gear-wheel, 80 as shown in Fig. 1.

On the lower end of the shaft carrying the pinion 9, is keyed a beveled pinion 61, adapted to be engaged by oppositely disposed beveled gears 62 and 63, loosely 90 mounted on the shaft 59 and adapted to be connected therewith by a clutch 64.

Provision is made for shifting the entire loading mechanism. This can be conveniently done by means of a sprocket chain 95 65, passing around sprocket wheels, one on the counter-shaft and the other secured to one of the wheels. On the counter-shaft is keyed a beveled wheel 66, adapted to be engaged by oppositely disposed pinions 67 100 and 68, loosely mounted on the shaft 59 and adapted to be connected thereto by a clutch 70.

The scoop may be caused to move around the shaft 10, through the material to a position to retain the material, and shifted around the shaft 13 so as to maintain it in upright position during the swing to discharging position. In order to hold the scoop in operating position, while being forged into the material to be removed, an arm 71 is secured to one of the arms 11 in such position as to bear on a shoulder or abutment 72 on the scoop, when the latter is in receiving position, said shoulder being 115 preferably formed on the flange 15.

It will be observed that the scoop is shifted radially as regards the axis of movement of the boom or outrigger, and that when swung to discharging position the material is dumped through the annular base of the boom, and the circular track on which the boom turns, is carried by the receiving hopper or car. This construction will permit loading being effected at any point in an 120 arc of over 180 degrees.

I claim herein as my invention:

1. In a loading mechanism, the combination of a receiving hopper, an outrigger mounted on said hopper, arms pivotally con- 130

nected to the outrigger, a scoop pivotally supported on the arms, means for swinging the arms on their pivotal supports, and means for turning the scoop around the pivotal connection of the arms.

2. In a loading mechanism, the combination of a receiving hopper, an outrigger movable on the hopper around a vertical axis, a scoop carried by the outrigger and means 10 for moving said scoop in non-concentric arcs

of circles having horizontal axes to gather material and discharge the same into the hopper, the axis of one of the arcs being supported on the outrigger.

In testimony whereof, I have hereunto 15 set my hand.

GEORGE F. DILLIG.
